NAPOLEON B. DOUGLASS, OF BERKELEY, CALIFORNIA.

WALL-BED SPRING-COUNTERBALANCE.

1,295,449.

Specification of Letters Patent. Patented Feb. 25, 1919.

Application filed May 27, 1915. Serial No. 30,798.

To all whom it may concern:

Be it known that I, NAPOLEON B. DOUGLASS, a citizen of the United States, residing at Berkeley, in the county of Alameda and State of California, have invented new and useful Improvements in Wall-Bed Spring-Counterbalances, of which the following is a specification.

This invention relates to wall beds, and pertains especially to a spring balance therefor.

The object of the present invention is to provide a simple, practical, compact counter-balancing means, especially designed for use with wall beds, or beds or other devices which are horizontally pivoted and adapted to be moved from a horizontal to a vertical position, and vice versa. Among the especial objects of the invention are: to design a spring counter-balance which at all times will be completely out of the way; which will be out of sight particularly when the bed is horizontal; which will be within the frame of the bed; which will permit the bed to be so fulcrumed when the bed is down that there will be no possibility of the bed frame tipping up accidentally; which will provide for adjustability of the springs so as to vary the tension; which will provide lightness and compactness for shipping and for the further advantage of reducing the weight on the turnable support for the bed; which, when the bed is up, practically removes the tension from the springs except that which is sufficient merely to keep the bed in upright position and not permit it to fall over when turning the support; which permits the tension to be applied and the bed to be so balanced that the life of the springs are not effected injuriously; which will permit the bed to be hung close to the turning support and yet provides sufficient room for the vertical movements of the bed. There are other objects and advantages which will be apparent hereinafter.

Having reference to the drawings—

Figure 1 is a detail perspective view of the head of the bed.

Fig. 2 is a detail view of the carrying mechanism.

Fig. 3 is a detail elevation of same.

Fig. 4 is a detail perspective of the journal bearing.

Fig. 5 is a detail perspective of the fulcrum shaft.

Fig. 6 is a detail perspective of the pin carrying bracket.

Fig. 7 is a detail perspective of the bed carrying bracket.

A represents a reversible panel of the character shown in my prior Patent #1,006,068, dated October 17, 1911, and so mounted on arms as 2, as to swing through an arc of 180 degrees, carrying a bed frame 3 with it.

The present invention pertains especially to the mounting of the bed 3 on the panel A so as to counter-balance the bed in a swinging position from vertical to horizontal. I desire to have it understood that while this bed mounting and counter-balance has been especially designed for use in conjunction with a swinging panel or support as A, manifestly, the invention is not limited to any particular kind of support, reversible or otherwise. In practice, these beds are made this way and so I describe them.

The bed mounting comprises a pair of brackets 4, secured to the support or door A on each side of the bed; each bracket having an upwardly extending portion 5 with a vertically extending reversely curved guide slot 6 forming a cam groove for a roller projection 7 on a side bar of the bed frame 3. The projecting pin 7 forms part of a bracket 8 secured to a side bar adjacent to the head end of the bed frame; it being understood that there is one of these brackets 8 with the pin 7 on each side of the bed, as there is one pin for each guide slot 6. Cooperating with pins 7 and guide slot 6 are a pair of supporting fulcrum links 9, the lower ends of which are fulcrumed at 10 to the brackets 4, the upper ends being secured to the fulcrum shaft 11, which extends across beneath the bed frame and just behind the rollers 7, and which shaft 11 has its ends journaled in boxes 12 on the side bars of the bed frame. A convenient

method of attachment of the links 9 to the fulcrum shaft 11 is to contract the upper ends of the links 9, as shown in Fig. 5, and pass them through slots in shaft 11 locking the projecting ends by means of cotter pins 13; the cotter pins and projecting ends of links 9 being contained within a depression or pocket 14 at the top of the fulcrum shaft 11. 15 are helical torsion springs surrounding the ends of the shaft 11 inside the bed frame, with one end of the springs adjustably anchored by a stop collar 16 to the shaft; the other end anchored to the bed frame by engaging the hooked end 17 of the spring with a projecting lug 18 of the journal box 12.

In order to prevent binding of the springs with the bar, the outer end of each spring passes over a complementary segmental extension 20, Fig. 4 on the sleeve box 12 approximate to its connection with the lugs 18; the segmental projections 20 keeping the springs out of frictional contact with the shaft 11. The inner adjacent ends of the springs 15 engage with stops or lugs 21 on the sleeves 16, which latter are provided with hexagonal surfaces for engagement with a wrench, and are perforated as at 22 to permit pin 23 to pass therethrough and through corresponding perforations 24 in shaft 11. By means of the pins and perforations and turnable collar 16 a nice adjustment of the springs can be effected after the bed is set up so as to adjust the springs to the weight to be carried to produce a more perfect counter-balance than if no such adjustment were afforded.

The inner end of the bed frame is preferably provided with a folding head board 40 and link connections 27 similarly as shown in my Patent #991,771, May 9th, 1911, coöperating with the head board automatically on the raising and lowering of the bed frame.

45 In operation the parts being assembled as described and the tension adjusted and the bed frame standing in upright position as in Fig. 2, all that is necessary to bring the bed into horizontal dotted line position shown in said Fig. 2 is for the operator simply to take hold of the upper foot end of the bed and pull it downward. The entire weight of the bed is carried on the links 9 and the guiding and control of the bed is 50 effected through the engagement of the pins 7 with the guide slot 6; the guide slot 6 being so curved as to allow the bed to swing slightly downward; as it is pulled down, the fulcrum of the bed, represented by the fulcrum shaft 11 and the links 9 swinging out correspondingly to give clearance. This construction enables the fulcrum to be put in close to the support A, and by bringing the fulcrum and pin 7 close together the bed

is prevented against accidental upward collapse. The general combination of the torsion spring, shaft 11, links and guide slots provides the advantages and accomplishes the objects hereinbefore set forth.

The mounting of the rod or fulcrum shaft 11 on links 9 and the pivoting of the bed frame on the shaft provides a floating fulcrum; by the method of mounting the torsion springs on the shaft, the counter-balancing is not interfered with by the various changes in position assumed by the floating fulcrum.

It will be manifest that various changes in details of construction may be effected without varying the principle of the invention.

Having thus described my invention, what I claim and desire to secure by Letters Patent is—

1. In a counter-balancing means for beds, 85 consisting in the combination of a bed frame, a pair of bed frame carrying links pivoted at one end, a fulcrum shaft rigidly supported on the links and upon which the bed is turnable in a vertical plane, torsion springs surrounding the fulcrum shaft and having one end connected with the bed frame, and the other end provided with anchorages on the shaft, the connections between the springs and bed frame comprising 90 lugs on the bed frame for the springs to engage, and sleeve members rigid with the bed frame extending beneath the adjacent ends of the springs to keep the springs out of binding contact with the shaft. 100

2. In a folding bed, a bed frame, links pivoted at their lower ends, a shaft rigidly connected to the upper ends of the links, a spring on the shaft connected thereto at one end, means to movably mount the frame on 105 the shaft ends, means associated with the mounting means and engaged with the other end of the spring to wind the latter on the shaft when the frame is lowered, and means associated with the last named means to prevent the spring from binding on the shaft. 110

3. In a folding bed, a bed frame, swinging links, a shaft rigidly connected to the upper ends of the links, a spring on the shaft having connection therewith at one end, a bearing connected to the bed frame and turnably receiving one end of the shaft, means on said bearing to engage the other end of the spring, and an extension on the bearing interposed between said last named end of 115 the spring and the shaft. 120

4. In a folding bed, a bed frame, a shaft, floating means rigidly supporting the shaft and located between the shaft ends so as to leave the latter free, springs surrounding 125 the shaft and connected thereto at their inner ends, bearings connected to the bed frame and turnably engaged with said free

ends of the shafts, means on the bearings extending inwardly toward and engaged with the outer ends of the springs, and means on the bearings extending over the free shaft 5 ends and interposed between the latter and the outer ends of the springs to prevent the latter from binding on the shaft.

In testimony whereof I have hereunto set my hand in the presence of two subscribing witnesses.

NAPOLEON B. DOUGLASS.
